UNITED STATES PATENT OFFICE.

LOUIS C. HAMEL, OF APPLETON, WISCONSIN.

WINDMILL-OILER.

1,100,970.

Specification of Letters Patent. Patented June 23, 1914.

Application filed August 14, 1913. Serial No. 784,726.

To all whom it may concern:

Be it known that I, LOUIS C. HAMEL, a citizen of the United States, residing at Appleton, in the county of Outagamie and 5 State of Wisconsin, have invented certain new and useful Improvements in Windmill-Oilers, of which the following is a specification.

This invention relates to windmills and 10 has for its object to provide a novel and improved lubricating device in connection with the pump rod, said device being entirely automatic in its operation. This object is attained by means of a combination and arrangement of parts to be hereinafter described and claimed, and in order that the invention may be better understood, reference is had to the accompanying drawings in which—

20 Figure 1 is a side elevation of a fragment of the head or upper portion of a windmill; Fig. 2 is an enlarged vertical section at a right angle to the line 2—2 of Fig. 1.

Referring specifically to the drawings, 10 25 denotes the swiveled head of a windmill having a horizontal bearing 11 for the wheel shaft 12 which drives the pump rod 13, said shaft carrying a wrist-wheel 14 which is connected, by means of a pitman 15, to a 30 plunger 16 carried by the upper end of the pump rod. The head carries a tubular slideway 17 for the plunger, said slideway having a side slot 18 in which the connection 19 between the plunger and the pitman works.

35 The upper end of the plunger 16 is formed with a pocket 20 which serves as an oil cup, the same moving up and down with the plunger when the latter is in motion. Projecting down into the slideway 17 is an oil 40 distributor 21, the same comprising a flat spring which is hooked over the top edge of the slideway, and is held in place by a cap 22 fitting over the top of the slideway.

In operation, when the oil cup 20 rises, the 45 free or loose lower end of the spring 21 passes into the cup and dips into the oil therein. As the oil cup moves downward, away from the spring, the oil clinging to the spring is applied by the latter to the wall of the 50 slideway by the spring touching said wall. Thus all parts at this point are lubricated automatically and any surplus oil is scraped or shaved off the slideway when the cup rises, the top edge of the latter being bevelled to a sharp edge as indicated at 22.

The spring is tensioned to bear normally against the wall of the slideway, and its free end has a slight outward bend as shown in Fig. 2 which is engaged by the beveled edge 22^a when the cup rises, whereupon the spring is forced inward so that it moves inward away from the wall of the slideway and dips into the cup as the latter continues to rise.

I claim:

1. A lubricator comprising a vertically reciprocatory plunger having an oil cup at its upper end, a tubular slideway in which the plunger works, and an oil distributor mounted in the slideway to dip into the oil cup on the up stroke of the plunger.

2. A lubricator comprising a vertically reciprocatory plunger having an oil cup at its upper end, a tubular slideway in which the plunger works, and an oil distributor mounted in the slideway, said distributor being normally in contact with the wall of the slideway, and dipping into the oil cup and moving outward from said wall on the up stroke of the plunger.

3. A lubricator comprising a vertically reciprocatory plunger having an oil cup at its upper end, a tubular slideway in which the plunger works, and an oil distributor mounted in the slideway, said distributor being normally in contact with the wall of the slideway, and in the path of the cup and engageable thereby to move outward from said wall and dip into the cup on the up stroke of the plunger.

4. A lubricator comprising a vertically reciprocatory plunger having an oil cup at its upper end, a tubular slideway in which the plunger works, and an oil distributor mounted in the slideway, said distributor comprising a resilient member secured at its upper end and having its lower end free and in the path of the cup to dip thereinto on the up stroke of the plunger, said member being normally in contact with the wall of the slideway.

5. A lubricator comprising a vertically reciprocatory plunger having an oil cup at its upper end, a tubular slideway in which the plunger works, and an oil distributor mounted in the slideway, said distributor comprising a resilient member normally in contact with the wall of the slideway and made fast thereto, its lower end being free and in the path of the cup to dip thereinto on the

up stroke of the plunger, said free end of the member having an outward bend engageable by the top edge of the cup.

6. A lubricator comprising a vertically reciprocating plunger having an oil cup at its upper end, a tubular slideway in which the plunger works, and an oil distributor mounted in the slideway, said distributor comprising a resilient member normally in contact with the wall of the slideway and made fast thereto, its lower end being free

and in the path of the cup to dip thereinto on the up stroke of the plunger, said free end of the member having an outward bend engageable by the top edge of the cup, said edge being beveled. 15

In testimony whereof I affix my signature in presence of two witnesses.

LOUIS C. HAMEL.
